HARRY E. TOWNSEND, OF BROOKLYN, NEW YORK.

LABELING MACHINE.

Application filed December 15, 1925. Serial No. 75,507.

My invention relates to machines for handling and wrapping articles, and has special reference to machines for wrapping and securing a label about a cylindrical package such as a package of hard candies that are in the form of circular disks and arranged in a stack or roll.

An object of the invention is to provide a wrapping machine of this character which is simple in construction, and rapid and efficient in operation.

Another object of the invention is to provide novel and improved mechanism for handling articles.

With these and other objects in view, the features of the invention consist in certain constructions, arrangements and combinations of parts hereinafter described and claimed, the advantages of which will be obvious to those skilled in the art.

The several features of the invention will be clearly understood from the following description and accompanying drawings, in which:

Figure 1 is a longitudinal sectional view of the upper portion of a machine embodying the features of the invention in their preferred form;

Fig. 2 is a similar view of the lower portion of the machine;

Fig. 3 is a vertical sectional view taken substantially on the lines 3—3 of Figs. 1 and 2;

Fig. 4 is a side elevation of an upper portion of the machine looking in the opposite direction from Fig. 1;

Fig. 5 is a sectional view taken substantially on the line 5—5 of Fig. 3;

Figs. 6 and 7 are detail sectional views taken on the lines 6—6 and 7—7 respectively, of Fig. 3;

Fig. 8 is a sectional view taken on the line 8—8 of Fig. 4;

Fig. 9 is a sectional view, taken on the line 9—9 of Fig. 5;

Fig. 10 is a detail front elevation of a label supporting basket and certain parts associated therewith;

Figs. 11, 12 and 13 are sectional plan views taken on the line 11—11 of Fig. 1, illustrating particularly the article conveying mechanism of the machine in different positions;

Figs. 14, 15, 16 and 17 are diagrammatical views illustrating particularly certain parts of the wrapping mechanism of the machine,

the different views showing the parts in different positions; and

Fig. 18 is a view in perspective of a cylindrical package having a label wrapped about its cylindrical surface by my improved machine.

The machine illustrated in the drawings is particularly adapted for use in wrapping a label 2 about a cylindrical package 4 (Fig. 65

18), the ends of the label overlapping and being glued or pasted together. This machine may be used in connection with the machine described and claimed in my pending application, Serial No. 74,292, filed December 9, 1925, for sealing packages of hard candies and similar articles that have at least one wrapper of wax paper. In said sealing machine the packages when completed are conveyed from the machine by 70

means of a sprocket chain which is indicated at 6 in Fig. 1, having outwardly spaced blades 8 upon which the packages are supported as they are carried downwardly. In the present machine vertically arranged 75

guide plates 10 are arranged adjacent to opposite sides of the vertical stretch of the chain and serve to hold the packages on the blades 8 until they reach the lower edge of the forward guide plate, where they are 80

successively picked off of the blades by a conveying mechanism which conveys them to the wrapping mechanism of the machine which wraps a label about each package. During the transfer of each package from 85

the conveyor chain to the wrapping mechanism, it centrally engages a label which has previously been positioned across the path thereof and carries the label therewith

to the wrapping mechanism, glue or paste 90 being applied to one edge of the label so as to cause the overlapping ends of the label to be secured together during the wrapping operation.

This conveying mechanism comprises a carrier block 12 (Figs. 1, 10, 11 and 12) which is mounted to slide longitudinally on a pair of guide rods 14, having their ends secured in brackets 16 projecting from the machine frame. Longitudinally extending 100

levers 18 are pivotally mounted on vertical pivot pins 20 which extend through laterally projecting ears 22 on the carrier block. The forward ends of the levers are provided with inwardly projecting jaws 24 which, when 105

the levers are turned in one direction, are adapted to engage the ends of a package 110

positioned between them. The inner ends of the jaws are substantially flat, and are provided with inward projections 26 which, when the jaws engage the article, extend over the ends of the back thereof. The inner end portions of the jaws have their top and bottom surfaces inclined rearwardly and inwardly for clearing parts of the wrapping mechanism. The levers 18 are urged in a direction to close the jaws 24 by means of expansion springs 28, each of which is coiled about a transverse rod 30 that has its inner end pivotally mounted on an upstanding pin 31 secured on the carrier block and its outer end extending through an aperture in an upwardly projecting stud 32 on the rear end portion of the associated lever, the spring being interposed between the stud and a nut 34 secured on the inner end of the rod 30. The levers are adapted to be turned to open the jaws by means of abutment plates 36 that are adapted to engage rolls 38 mounted on the rear ends of the levers.

Rods 42 are mounted to slide longitudinally in grooves 40 in the outer edges of the levers 18, and are held in the grooves by pins 44 that are secured to the levers and extend through elongated slots 46 in the rods. The forward ends of the rods are provided with inwardly projecting fingers 48. The rods are urged rearwardly with relation to the levers 18, by means of springs 50, each of which is coiled about a sliding bolt 52 having one end secured to a stud 54 on the rear end of the rod, and its forward end extending through an aperture in one of the pins or studs 44 so as to be guided thereby, the spring being interposed between the stud 44 and nuts 56 secured on the bolt. The rearward movement of the finger carrying rods 42, during the rearward or retracting movement of the carrier 12, is limited by the engagement of abutment rolls 58 mounted on the rear ends thereof with the rear bracket 16. The carrier block 12 is further provided with two forwardly projecting rods 60 that are secured in sockets in the forward side of the block, and are adapted to be projected through apertures in the forward bracket member 16 and in the rear guide plate 10 during the advancing movement of the block.

With this construction, during the advancing movement of the carrier block 12 the forward ends of the pins 60 engage one of the packages on the conveyor chain 6, remove it from its supporting blade, and push it forwardly therewith upon a horizontal platform comprising a plate 62, and beneath a downwardly spring pressed holding member 64 that engages the upper portion of the cylindrical surface of the package and holds it in position, the underside of the holding member being curved to fit the package.

When the package has reached this position,

the carrier block 12 is at the limit of its advancing movement. Previously to the start of the retracting movement of the carrier block, the abutment plates 36 are moved inwardly so as to act on the rolls 38 on the rear ends of the jaw carrying levers 18 to turn the levers in a direction to open the jaws. The jaws are held open by the abutment plates 36 during the entire retracting movement of the carrier block 12, the rolls 38 riding on the abutment plates. When the carrier block reaches the limit of its retracting movement, the jaws 24 are positioned opposite the ends of the package that has been delivered to the station beneath the holding member 64, and when the jaws reach this position, abutment plates 36 are retracted to permit the springs 50 to close the jaws on the ends of the package. During the next advancing movement of the carrier block 12, the gripping jaws carry the package from beneath the holding member 64 and to the wrapping mechanism. During this movement of the gripping jaws to convey the package to the wrapping mechanism, the package engages the central portion of a label 2, which has been delivered previously across the path of movement of the package, and the label is carried with the package to the wrapping mechanism. The rearward movement of the finger carrying rods 42 during the rearward or retracting movement of the carrier block 12 which is limited by the engagement of their rear ends with the rear supporting bracket 16, as above described, so positions the fingers 48 that when the levers 18 are turned to close the jaws upon the ends of the package, the ends of the fingers are positioned adjacent to the front side of the label, so that when the package is advanced by the gripping jaws into engagement with the label, the fingers act to tightly grip the label upon the forward side of the package and then to move with the jaws so as to hold the label in position as the package is carried to the wrapping mechanism. It will be apparent when the jaws are open to release the package after it reaches the wrapping mechanism, the fingers will be carried with the jaws out of engagement with the label.

The carrier block is actuated through a link 66 which has one end pivotally connected with depending ears on the under side of the block and its other end pivotally connected with the upper end of a lever 68, which is pivotally mounted at 70 on the lower portion of the machine frame, and its lower end carries a cam roll 72 that engages a groove in a cam 74 carried by a driven shaft 76 journaled in suitable bearings in the lower portion of the machine frame. The abutment plates 36 for opening the gripping jaws are formed upon the upper end of levers 78 that are pivotally mounted at 80

on the machine frame, and their lower ends carry cam rolls that engage cam surfaces on opposite sides of cam disks 84, the rolls being held in engagement with the cam surfaces by means of a coiled spring 86 connecting the lower arms of the levers.

The package holding member 64 is formed on the free end of an arm 88 secured on one end of a rock shaft 90, which is urged in a direction to press the block downwardly by means of a coiled spring 92 connected with an arm 93 secured thereto (Figs. 4 and 9).

The label which is delivered across the path of each package as above described, is supported in a basket 94, having its front and rear sides inclined downwardly toward each other with the lower end of the forward side turned rearwardly to form a support for the lower edge of the label, the rear side of the basket forming a continuation of the supporting plate 62 upon which the package is supported at the station beneath the holding member 64. The front and rear sides of the basket 94 are each provided with a series of vertical slots 96 (Figs. 1 and 10), the slots in the two sides being arranged opposite to each other. A glue applying roll 98 is arranged adjacent the rear side of the basket, and is provided with a series of flanges 100 arranged opposite to the slots in the walls of the basket. The glue roll 98 has reduced ends (Fig. 9) that are journaled in bearings in the end walls of a glue pot 102. The glue pot is mounted on a supporting arm 104 pivoted on a pin 106 which extends through ears on said arm and on a supporting block 105 on the base plate 107 of the machine frame, and is held on the supporting arm by means of a dove-tail joint connection 108 so as to permit it to be easily removed and replaced. The glue is supplied to the peripheral surfaces of the flanges 100 of the glue roll, by means of a supply roll 110 that rotates in engagement with the peripheral surface of said flanges and is partially immersed in the glue within the pot. The roll 110 has its ends journaled in the ends of the glue pot and is driven by a pinion 112 (Fig. 5) that engages a gear 114 secured on one end of the glue roll 98. The gear 114 carries a laterally projecting pin 116 (Fig. 9) which is adapted to be engaged by the end of an arm 118 carried by a shaft 120 journaled in an upright bracket 122 on the supporting arm 104. The pin and arm driving connection with the glue roll 98, does not interfere with the removal of the glue pot, as above described. The arm carrying shaft 120 is driven from a driven shaft 124, through a gear 126 secured on one end thereof which, through an idle gear 128, is connected with a gear 130 carried by the driven shaft 124. The axis of the driven shaft 124 is parallel with the axis of the pivot pin 106 on which the supporting arm

of the glue pot is mounted, and the axes of the shaft and pin, are arranged sufficiently close together so as to permit the glue pot to be oscillated without disturbing the driving connection with the glue rolls. The shaft 124 is continuously driven by a belt 127 that passes over a pulley secured on the shaft and a pulley carried by a drive shaft 129 journaled in the lower portion of the machine frame.

The glue pot and the rolls carried thereby, are rocked back and forth during the operation of the machine by means of a rod 132 having one end pivotally connected with the outer end of the shaft 120, and its other end bifurcated to straddle a driven shaft 134 which carries a cam 136 that engages a cam roll 138 carried by the rod 132, the cam roll being held in engagement with the cam by means of a spring 140 connected with the rod. The shaft 134 is journaled in suitable brackets on the base plate 107 and is driven by a sprocket chain 142 that passes over a sprocket wheel thereon and a sprocket wheel carried by the drive shaft 129.

When a label has been delivered into the basket 94 and previously to the engagement of the package with the label, the glue pot 102 is rocked to carry the glue roll 98 forwardly so as to cause the flanges thereof to pass through the slots in the rear side wall of the basket and apply glue against the lower edge portion of the label, the front side wall of the basket providing a support for the label. In case, for any reason, a label fails to be delivered to the basket previously to this forward movement of the glue roll, the flanges of the glue roll enter slightly the slots in the forward side wall of the basket, and thus the glue roll will not strike and daub glue over any portion of the walls of the basket.

The labels are supplied to the machine from a magazine 146 in which they are held in upright position in a stack. The labels are forced forwardly against flanges at the forward end of the magazine, one of which is shown at 148 (Fig. 1), by means of a plunger head 150 which is pivotally mounted on the rear end of a horizontal stud 152 having its forward end secured in the lower end of a depending arm 154 carried by a horizontal rod 156. This rod is mounted to slide in suitable bearings in the top of the machine frame and is pressed rearwardly by means of a weight 158 connected with the rear end thereof by a cord 160 that passes over suitably arranged guide pulleys 162.

The labels are adapted to be one by one fed from the magazine, by means of a roll 164 which carries a segmental friction pad 168 for engagement with the labels. The friction roll 164 delivers each label to a pair of feed rolls 170 which in turn feed the label between rolls 172 and cooperates therewith

to deliver the label across the path of movement of the package and into the basket 94, the label being guided during its passage from the upper to the lower feed rolls by upright guide pins 173. The feed rolls 172 are each provided with a series of spaced flanges 174, the flanges of one roll being opposite to the spaces between the flanges of the other roll, and entering said spaces 10 slightly.

The feed rolls 172 tend to feed the label into the basket 94, but the engagement thereof with the label is so light, that when the lower edge of the label strikes the bottom of 15 the basket they effect no further appreciable feeding action on the label, they then merely serving to support the upper end of the label until it is engaged by the package, whereupon the label is freely drawn from 20 between the rolls and out of the basket.

The friction roll 164 is rotated intermittently one complete revolution, and the feed rolls 170 are rotated simultaneously at the same surface speed therewith, the label feeding and supporting rolls 172 being rotated continuously. The friction roll 164 is shown in Fig. 1 in the position it assumes when the roll is at rest, the friction pad of the roll being in engagement with the outer label in 25 the stack and having carried the lower end of the label a sufficient distance out of the magazine to cause it to be engaged by the feed rolls 170. The label is in this position when the gripping jaws are at the limit of 30 their advancing movement to present a package to the wrapping mechanism, the package conveying mechanism also having delivered the next package to be acted upon to the station beneath the holding member 64. The 35 friction roll 164 together with the feed rolls 170 remain at rest during the first part of the retracting movement of the gripping jaws to engage the package at said station. Before, however, the gripping jaws have advanced the latter package, the friction roll 40 164 is again rotated one complete revolution to cooperate with the feed rolls 170 to feed the label protruding from the magazine, between the supporting rolls 172 and into the 45 supporting basket 94, ready to be engaged by said package as it is conveyed to the wrapping mechanism. Also during the revolution of the friction roll 164, the next label in the stack is carried downwardly by the 50 roll so as to position its lower end portion between the feed rolls 170, whereupon the roll is brought to rest as above described.

The friction roll 164 is carried on one end of a shaft 175, the other end of which extends through and is journaled in a bearing 176 (Figs. 4 and 8) on the machine frame. A ratchet wheel 178 is loosely mounted on the shaft 175, and a gear 180 is secured on 55 its hub and is operatively engaged by a rack 181 which is mounted to slide vertically

in bearings in the machine frame. The ratchet wheel 178 is provided with a single tooth that is adapted to engage a tooth on a pawl 182 pivotally mounted on an arm 184, the pawl being held toward the periphery of the ratchet wheel by a spring 186 connected therewith. The arm 184 is secured on the shaft 175. With this construction, during the upward movement of the rack 181 the ratchet disk 178 acts through 70 the pawl 182 to rotate the friction roll carrying shaft 175 one complete revolution, the shaft being at rest during the downward movement of the rack.

The feed rolls 170 are driven with the 80 friction roll 164, through a gear 188 secured on the hub of the pawl carrying arm 184, and connected through an idler 190 with a gear 192 which is secured on the shaft of one of the feed rolls, and engages a gear 85 194 secured on the shaft of the other feed roll.

The rack 181 extends downwardly through an opening in the base plate 107 and has its lower end connected by a link 90 196 with one end of a cam lever 198 pivoted on the machine frame and carrying a cam roll 200 that engages a groove in a cam 202 carried by the drive shaft 129.

The label feeding and supporting rolls 95 174 (Figs. 4 and 9) have their shafts extended through and journaled in bearings in the machine frame. The shafts are operatively connected by gears 204 secured thereon, and are driven by a belt 206 that 100 passes over a pulley secured on one of them and a pulley secured on the continuously driven shaft 124.

In the illustrated construction in case, for any reason, the conveying mechanism fails 105 to deliver a package to the station beneath the holding member 64 during the advancing movement of the carrier block 12, the label feeding mechanism, comprising the friction roll 164 and the feed rolls 170, is rendered 110 inoperative to feed a label into the basket 94 during that cycle of operation of the conveying mechanism, and this is accomplished without interfering with said cycle of operation of said conveying mechanism 115 or other parts of the machine. To provide for this, the upper end of the spring pressed arm 93 (Fig. 4) which is connected with the holding member 64, has its upper end operatively connected with one arm of a bell 120 crank 208. The end of the other arm of the bell crank is adapted, when the bell crank is turned in one direction and when the pawl 182 is at rest, to engage a tail piece 210 on the outer end of the pawl to 125 swing the pawl out of engagement with the tooth of the ratchet wheel 178. When a package is positioned beneath the holding member 64 the end of said arm of the bell crank is held out of engagement with the 130

pawl 182, but when there is no package thus positioned the spring 92 is permitted to turn the bell crank to disconnect the pawl. It will, therefore, be apparent that as the conveying mechanism normally acts to deliver a package to the station beneath the holding member 64 before a label therefor is delivered to the basket 94, in case the conveying mechanism fails to thus position a package 10 during any one of the cycles of operation thereof, the label feeding mechanism will be rendered inoperative to deliver a label during the remainder of that cycle of operation of the said conveying mechanism.

15 The wrapping mechanism of the machine illustrated in the drawings is provided with wrapping rolls 214 preferably of rubber or other resilient material (Figs. 1, 3 and 5), that are mounted on a turret 216. This turret is secured on one end of a shaft 218 that has its other end portion extended through and journaled in bearings in upright supporting frames 220 mounted on the base plate 107. The turret is provided with 25 flanges 222 on its ends.

The wrapping rolls 214 are arranged in a series of four sets, with four rolls in each set which in turn are arranged in pairs. Each set of rolls is adapted to receive a package 30 and its label between them, and adapted to be operated to wrap the label about the package. Each pair of rolls of each set is associated with a swinging carrier 226 which has inwardly projecting ears 228 pivotally 35 mounted on a shaft 230 which extends through and is journaled in the flanges 222 of the turret. One of the wrapping rolls of each pair is secured directly on the shaft 230, and the other wrapping roll which is 40 the outer one, is secured on a shaft 232, having its ends extended through and journaled in projecting ears 234 at the ends of the swinging carrier. The left hand outer wrapping roll of each set, viewing Fig. 1, is 45 made in sections that are spaced apart to permit the ends of tucker fingers 236 to extend between them, the other ends of the tucker fingers being secured to a web or bar 238 connecting the ends of the swinging carrier. The swinging carriers 226 associated 50 with each set of wrapping rolls are adapted to be turned about the axes of their pivot shafts 230 to move the outer rolls thereof away from each other so as to permit a 55 package and its wrapper to be inserted between and against the inner rolls. The carriers of each set are, however, pressed toward each other, by means of a coiled spring 240 having its ends connected with the carriers. 60 The inward movement of the carriers, when there is no package between them, is limited by the engagement of projecting lugs 242 thereon with stop pins 244 secured on the inner flange of the turret.

65 The swinging carriers 226 of each pair

are adapted to be thus turned to swing their outer rolls away from each other when the turret has carried the rolls into position to receive a package from the gripping jaws as shown in Fig. 1, by means of a cam plate 70 246 (Fig. 5) which is provided with an inwardly and downwardly inclined cam surface 248 for engaging a cam roll 250 mounted on the upper swinging carrier, and an upwardly and inwardly inclined cam 75 surface 252 for engaging a cam roll 254 mounted on the lower swinging carrier.

When the outer wrapping rolls of a set are opened as described, the gripping jaws 80 position the package against the inner two wrapping rolls of the set, as indicated in Figs. 1 and 15. When this occurs the cam plate 246 is retracted from the cam rolls carried by the swinging carrier which permits the spring 240 to cause the outer rolls 85 to be brought toward each other and against the package. The cam surfaces 248 and 252 are so shaped that the upper swinging carrier is moved inwardly in advance of the lower swinging carrier, which causes the 90 tucker fingers 236 carried thereby to bend the upper edge portion of the label downwardly over the back of the package, and at substantially the same time as this is effected, the upper wrapping roll engages the 95 adjacent portion of the label and holds it against the package. After the tucker fingers have thus acted to tuck in the upper edge portion of the label over the back of the package, the lower wrapping roll bends 100 the lower edge portion of the label upwardly over the other edge portion, as indicated in Fig. 16. As the edge portions of the wrapper are thus tucked in an overlapping relation, the gripping jaws are released 105 from the package and are returned to their position to receive the next package that is delivered to the station beneath the holding member 64. With all four rolls thus in engagement with the package the rolls are rotated to cause the package to revolve in a clockwise direction, viewing Fig. 1, so as to cause the label to be tightly drawn about the package and the overlying edge of the label to which glue has been applied to be pressed 110 tightly down upon the inner edge of the label. After the set of rolls that have thus received a package have been rotated a predetermined number of times, the turret is 115 rotated 90° in a counter-clockwise direction, viewing Fig. 1, so as to position the next succeeding set of wrapping rolls in a position to receive the next package that is advanced by the gripping jaws. In a similar manner, the other sets of wrapping rolls are 120 successively positioned to receive the packages from the gripping jaws. All of the wrapping rolls are rotated to rotate the package after a set has closed upon the package, and the rolls continue to rotate during 125 130

each movement of the turret, they being stopped when the turret is brought to rest, and remaining in stopped position until the last package received has been engaged by 5 the four rolls of the set to which it is presented.

By the time a set of rolls has reached a position directly beneath the axis of the turret, the package held thereby has been rotated sufficiently to cause the label to be tightly wrapped thereabout and to permit the glue that secures the overlapping edges of the label to dry. When the package reaches said position, the swinging carriers 10 are opened to permit the package to drop by gravity down into a forwardly and downwardly inclined chute 256 which delivers the package to a conveyor belt 258 for conveying the packages from the machine. The 15 swinging carriers are adapted to be opened to thus discharge the package by means of a vertically movable wedge shaped cam plate 260, the inclined cam surfaces of which act on the cam rolls 250 and 254. When 20 the package has been discharged the cam plate 260 is retracted to permit the carriers to close.

The cam plate 246 is secured on the upper end of a rocker arm 262 which has its lower 30 end secured on one end of a pivot shaft 263 (Figs. 2 and 3) which is mounted in a bracket secured on the under side of the base plate 107. An arm 264 is secured on the other end of the pivot shaft and carries a cam roll which engages a cam groove 266 in a cam carried by the drive shaft 129.

The cam plate 260 (Fig. 5) is provided with a vertical guide slot 268 through which the shaft 134 extends. This cam plate is 40 secured on the upper end of a rod 270, the lower end of which carries a forked guide plate 272 (Figs. 2 and 3) that straddles the shaft 129 and carries a cam roll that engages a cam groove 274 in a cam disk carried by 45 the shaft 129.

The driving connection for the turret 216 comprises a gear 276 secured on the further end of the turret shaft 218, that is operatively engaged by a gear 278 secured on a 50 short shaft 280 which extends through the outer supporting frame 220 and carries on its inner end the driven member 282 of a Geneva connection. The driving member thereof comprises a cam roll 284 which is carried by a rotating arm 286 secured to the shaft 134, the driven member of the geneva being provided with suitably arranged pockets 287 for receiving the cam roll.

The mechanism for driving the wrapping 60 rolls carried by the turret comprises a pinion 288 which is secured on one end of the shaft that carries the outer roll on each swinging carrier 226. Each pinion 288 engages an idle gear 290, which in turn engages a pinion 65 292 on the end of the shaft 230 that carries

the inner roll. The several pinions 292 engage a gear 294 which is secured on a sleeve 296 loosely mounted on the turret shaft 218 and carrying a pinion 298 that engages a gear 300 secured on the end of a short shaft 302 which extends through and is journaled in the inner upright 220. A driven member 304 of a Geneva connection is secured on the other end of the shaft 302 and is provided with a series of suitably arranged pockets 306 70 that are adapted to receive actuating cam rolls 308 carried by the actuating arm 286. The pockets in the driven members 282 and 304 of the two Geneva connections are in each case six in number. The provision, 75 however, of two actuating rolls 308 for the driven member 304 that are spaced 120° apart, instead of a single roll as for the driven member 282, results in the wrapping rolls being driven both during each movement of the roll carrying turret 216, and also just previous to said movement and immediately after a set of rolls have closed upon the package presented thereto, as above described.

As will be evident to those skilled in the art, my invention permits various modifications without departing from the spirit thereof or the scope of the appended claims.

What I claim is:

1. Mechanism for handling articles of substantially cylindrical form having, in combination, a conveyor for conveying a plurality of the articles in a substantially vertical plane to position them successively 100 at a given station, means for removing the articles from said conveyor as they reach said station and for advancing each article sidewise to a second station, means comprising a member adapted to be lifted by each 105 article as it reaches second station for engaging the upper portion of the cylindrical surface of the article to hold the article in position, and devices engaging the ends of the article for conveying it from beneath 110 said holding member.

2. Article handling mechanism having, in combination, a reciprocable carrier, means carried by the carrier for conveying a cylindrical article to a given station during the 115 movement thereof in one direction, and devices carried by said carrier for gripping the ends of the article between them while the article is at said station, and during the next movement of the carrier in said direction for conveying the article to another 120 station.

3. Article handling mechanism having, in combination, a reciprocable carrier, means carried by the carrier for advancing an 125 article to a given station during the movement of the carrier in one direction, and devices carried by the carrier and acting when the carrier reaches the limit of its movement in the opposite direction to grip the article 130

between them while at said station, and for advancing the article to another station during the next movement of the carrier in said first mentioned direction.

- 5 4. Article handling mechanism having, in combination, a reciprocable carrier, means carried by the carrier for advancing an article to a given station during the movement of the carrier in one direction, levers 10 pivotally mounted on the carrier having gripping jaws thereon adapted to grip the article between them, and means for turning the levers when said carrier is at the limit of its movement in the opposite direction to cause said jaws to grip the article while at said station, and for holding the levers in the position thus moved during the next movement of the carrier in said first mentioned direction.
- 20 5. Article handling mechanism having, in combination, a reciprocable carrier, means carried by the carrier for advancing an article to a given station during the movement of the carrier in one direction, levers 25 pivotally mounted on the carrier and having gripping jaws thereon, means comprising a spring acting to turn the levers in a direction to close said jaws, devices acting on said levers to open the jaws when the carrier 30 is at the limit of its movement in said direction and for holding the jaws open during the movement of the carrier in the opposite direction, and for releasing the jaws at the limit of its movement in the last mentioned 35 direction to permit them to close on the ends of the article at said station.

6. A machine for wrapping an elongated article having, in combination, wrapping mechanism, means for conveying an article 40 sidewise to said mechanism, means for feeding a wrapper across the path of movement of the article whereby it is engaged by the advancing side of the article during the movement of the latter toward said mechanism, and devices acting upon engagement 45 of the article with said wrapper to hold the wrapper against said article during the continued movement of said article toward said mechanism, said devices being movable in a 50 direction transversely of the path of movement of the article into and out of said path, and means for thus moving said devices outwardly so as to position them out of engagement with said wrapper after said article 55 and wrapper reach said wrapping mechanism.

7. A machine for wrapping an elongated article having, in combination, wrapping mechanism, means for conveying an article 60 to said mechanism, said means gripping the ends of the article, means for conveying a wrapper across the path of the article whereby it is engaged by the advancing side of the article during the movement of the latter toward said mechanism, and devices 65

carried by said conveying means acting upon engagement of the article with said wrapper to hold the wrapper against said advancing side of the article during the continued movement of said article toward said mechanism, and to release said wrapper when the article has reached said wrapping mechanism.

8. A machine for wrapping an elongated article having, in combination, wrapping mechanism, a carrier movable toward and from said mechanism, gripping jaws carried by the carrier adapted to grip the ends of an article between them and to convey it sidewise to said wrapping mechanism, and devices comprising inwardly projecting fingers mounted on the carrier for engaging said wrapper to hold it against the advancing side of said article upon engagement of the article with said wrapper and during the continued movement of said carrier toward said wrapping mechanism.

9. A wrapping machine having, in combination, wrapping mechanism, a carrier movable toward and from said mechanism, gripping jaws carried by the carrier adapted to grip an article placed between them and to convey it to said wrapping mechanism, devices comprising inwardly projecting fingers mounted on the carrier for engaging said wrapper to hold it against said article upon engagement of the article with said wrapper and during the continued movement of said carrier toward said wrapping mechanism, and means for releasing said gripping jaws 100 from the article and for releasing said holding devices from the wrapper when said article and wrapper reach said wrapping mechanism.

10. A wrapping machine having, in combination, wrapping mechanism, means for conveying an article to said mechanism, and means for supporting a wrapper across the path of the article comprising a support for the lower portion of the wrapper, and a pair of rolls for lightly engaging the upper portion of the wrapper between them, each having a series of spaced flanges with the flanges of one roll entering slightly the recesses in the other roll, and means for rotating the rolls in a direction to tend to feed the wrapper downwardly.

11. A wrapping machine having, in combination, wrapping mechanism, means for conveying an article to said mechanism, means for feeding the wrapper across the path of the article whereby it is carried by the article to the wrapping mechanism, means for supporting the wrapper while in said position and for applying glue to one side thereof comprising a basket for receiving the lower portion of the wrapper having the lower portion of one side wall provided with a series of vertical slots, a glue applying roll arranged adjacent said slotted side 125 130

of said basket and provided with a series of spaced flanges arranged opposite to said slots, means for applying glue to the peripheries of said flanges and means for bodily 5 tipping said roll to cause its flanges to be inserted through said slots and into engagement with the lower portion of said wrapper.

12. A wrapping machine having, in combination, a turret, a plurality of sets of wrapping rolls carried by the turret, the rolls of each set being adapted to receive a cylindrical article between them, and upon rotation thereof to rotate the article by frictional contact therewith, means for inserting a package between the rolls of each set when the set is at a given station, means for rotating said rolls, and means for rotating the turret to position the several sets at said 20 station successively, the rolls of each set when in engagement with the article being so positioned as to hold the article from lateral movement in all directions.

13. A wrapping machine having, in combination, a turret, a plurality of sets of wrapping rolls carried by the turret, the rolls of each set being adapted to receive a cylindrical article between them and upon rotation thereof to rotate the article by frictional contact therewith, means for inserting an article between the rolls of each set when the set is at a given station, and for removing the article when the set is at another station, means for rotating the rolls, and 35 means for rotating the turret intermittently to position the several sets first at one and then at the other station successively, the rolls of each set when in engagement with the article being so positioned as to hold the 40 article from lateral movement in all directions.

14. A wrapping machine having, in combination, a turret, a plurality of sets of wrapping rolls carried by the turret, each set 45 consisting of four rolls adapted to receive a cylindrical article between them, and upon rotation of the rolls to rotate the article by frictional contact therewith; means for inserting an article between the rolls of each set when the set is at a given station, means for rotating said rolls, and means for rotating the turret to position the several sets at said station successively; the rolls of each set when in engagement with the article being so positioned as to hold the article from lateral movement in all directions.

15. A wrapping machine having, in combination, two carriers pivotally mounted with their axes arranged parallel to permit 60 them to swing toward and from each other, a pair of wrapping rolls having their axes arranged concentrically with the axes of the carriers, respectively, a second pair of wrapping rolls mounted on said carriers, respec-

tively, with their axes spaced from and arranged parallel with the axes of the carriers so as to permit a cylindrical article to be passed between them when the carriers are swung away from each other, and together with said first mentioned pair of rolls to 70 engage the article when the carriers are swung toward each other, means for yieldingly pressing the carriers toward each other, and means for rotating the rolls.

16. A wrapping machine having, in combination, a pair of wrapping rolls arranged parallel and spaced apart, a second pair of wrapping rolls arranged parallel to and spaced from the first pair, and adapted to be moved away from each other about 75 the axes of the rolls of the other pair, respectively, to permit a cylindrical article to be passed between them and when moved toward each other to co-operate with the first pair to hold the article 85 in position between them, means for yieldingly pressing the rolls of the second pair toward the other pair of rolls to cause the several rolls to yieldingly grip the article, and means for rotating the rolls to 90 rotate the article.

17. A wrapping machine having, in combination, a pair of wrapping rolls arranged parallel and spaced apart, a second pair of wrapping rolls arranged parallel to and spaced from the first pair, and adapted to be moved away from each other to permit a cylindrical article to be passed between them and when moved toward each other to co-operate with the first pair to hold the article 95 in position between them, means for yieldingly pressing the rolls of the second pair toward the other pair of rolls to cause the several rolls to yieldingly grip the article, a turret upon which the several rolls are 100 mounted, means for rotating the turret intermittently to position said rolls alternately at two given stations for predetermined intervals of time, means acting when the rolls are positioned at each station to move said 110 second pair of rolls away from each other, and means for rotating the rolls during the rotation of said turret.

18. A wrapping machine having, in combination, a turret, a plurality of sets of wrapping rolls mounted on the turret, the rolls of each set adapted to be relatively opened and closed upon a cylindrical article placed between them, the rolls when open permitting the article to be inserted and removed, 115 means for yieldingly holding the rolls of each set closed so as to yieldingly grip an article positioned between them, means for opening the rolls of each set when they are positioned at a given station to permit an 120 article to be inserted between them, and after the article is inserted to permit them 125 to close, means for rotating the turret to suc-

cessively position said sets at said station, and means for rotating the rolls of the several sets during the rotation of the turret.

19. A wrapping machine having, in combination, a turret, a pair of carriers pivotally mounted on the turret to permit them to be swung toward and from each other on axes parallel to the axis of the turret, a spring tending to turn the carriers toward each other, wrapping rolls mounted on each carrier with their axes arranged parallel to the axis of the turret, the rolls on the two carriers adapted to receive a cylindrical article between them when said carriers are swung away from each other, and to engage the article when said spring returns the carriers toward each other, means for rotating the turret and for rotating said rolls, and means acting when the turret reaches a predetermined angular position to swing said carriers away from each other and to permit them to swing toward each other before the turret leaves said position.

20. A wrapping machine having, in combination, a plurality of rolls arranged in parallel relation and adapted upon rotation thereof to rotate a cylindrical article positioned between them by frictional contact therewith, means for separating two of the rolls to permit insertion of the article with its wrapper bent over the forward portion thereof and the edge portions of the wrapper extending rearwardly, a tucking device movable with one of said retractable rolls for bending one rearwardly extending edge portion of the wrapper over the back of the article when the roll is moved toward the article, means for thus moving the latter roll, and then moving the other retractable roll into engagement with the article, and means for simultaneously rotating all of the rolls.

21. A wrapping machine having, in combination, a pair of wrapping rolls arranged parallel and spaced apart, a second pair of wrapping rolls arranged parallel to and spaced from the first pair and adapted to be swung toward and from each other about the axes of the first mentioned rolls, respectively, means for yieldingly pressing said movable rolls toward each other, and means for effecting the rotation of all of the rolls.

22. A wrapping machine having, in combination, a pair of wrapping rolls arranged parallel and spaced apart, a second pair of wrapping rolls arranged parallel to and spaced from the first pair, pivotally mounted carriers for the rolls of the second pair, respectively, having their axes concentric with the axes of the rolls of the first pair, respectively, so as to permit them to be swung to move the rolls carried thereby toward and from each other, the several rolls being so arranged as to permit a cylindrical article to be placed in position between them when said carriers are swung away from each

other and to be engaged by all of the rolls when said carriers are swung toward each other, means for yieldingly pressing said carriers toward each other, and means for effecting the rotation of the rolls to rotate the article when positioned between them.

23. A wrapping machine having, in combination, a pair of wrapping rolls, arranged parallel and spaced apart, a second pair of wrapping rolls arranged parallel to and spaced from the first pair and adapted to be swung toward and from each other about the axes of the first mentioned pair of rolls, respectively, the several rolls being so arranged that when the rolls of the second pair are swung away from each other a cylindrical article may be inserted between them and when swung toward each other may cooperate with the first mentioned pair of rolls to engage the article, means for pressing the rolls of the second pair toward each other, means for inserting an article with a wrapper extending across the advancing side of the article in said position between the rolls when the rolls of the said second pair are swung away from each other, means for swinging the rolls of the second pair away from each other and when an article and its wrapper has been inserted in said position between the rolls for permitting first one and then the other of the rolls of the second pair to be moved toward the other roll of said pair, and means for effecting the rotation of all of the rolls.

24. A wrapping machine having, in combination, a pair of wrapping rolls arranged parallel and spaced apart, a second pair of wrapping rolls arranged parallel to and spaced from the first pair and adapted to be swung toward and from each other about the axes of the first mentioned pair of rolls, respectively, the several rolls being so arranged that when the rolls of the second pair are swung away from each other a cylindrical article may be passed between them and when swung toward each other may cooperate with the first mentioned pair of rolls to engage the article, means for pressing the rolls of the second pair toward each other, means for inserting an article with a wrapper extending across the advancing side of the article in said position between the rolls when the rolls of the said second pair are swung away from each other, means for swinging the rolls of the second pair away from each other and when an article and its wrapper has been inserted in said position between the rolls for permitting first one and then the other of the rolls of the second pair to be moved toward the other roll, and devices movable with said roll of the second pair that is first moved for bending one edge portion of the wrapper over the back of said article during the inward movement of said first moved roll,

and means for effecting the rotation of all of the rolls to rotate the article between them.

25. A wrapping machine having, in combination, a turret, a plurality of sets of wrapping rolls carried by the turret, the rolls of each set being adapted to receive a cylindrical article between them, means for yieldingly pressing the rolls with relation to each other against the surface of the article so as to rotate the article by frictional contact therewith upon rotation of the rolls, means for inserting a package between the rolls of each set when the set is at a given station, means for rotating said rolls, and means for rotating the turret to position the several sets at said station successively.

26. A wrapping machine having, in combination, a turret, a plurality of sets of wrapping rolls carried by the turret, the rolls of each set being adapted to be relatively moved away from each other to permit a cylindrical article to be positioned between them, and adapted to be relatively moved toward each other to engage the cylindrical surface of the article so as to rotate the article by frictional contact therewith upon rotation of the rolls, means for thus opening the rolls of each set when the set is at a given station to permit an article to be received between them and for thus closing the rolls on the article after the article has thus been presented to the rolls,

means for rotating said rolls, and means for rotating the turret to position the several sets at said station, successively.

27. A wrapping machine having, in combination, mechanism for wrapping a substantially cylindrical article when the article and its wrapper are presented thereto, means for thus operating said mechanism, devices movable toward and from said mechanism for successively presenting articles to said mechanism, means for feeding the wrapper across the path of each article whereby it is carried by the article to said wrapping mechanism, and means for rendering said wrapper feeding means inoperative independently of said wrapping mechanism and said devices to feed a wrapper upon failure of said device to present an article to said wrapping mechanism.

28. A wrapping machine having, in combination, a pair of wrapping rolls arranged parallel and spaced apart, and a second pair of wrapping rolls arranged parallel to the first pair and adapted to be swung toward and from each other and when swung toward each other to engage with the first pair a cylindrical article positioned between the two pairs so as to hold the article from movement in all directions.

In testimony whereof, I have signed my name to this specification this 14th day of December, 1925.

HARRY E. TOWNSEND.
